OSCILLATION GENERATOR

Frederick H. Scheer, Chicopee Falls, Mass., assignor to Westinghouse Electric & Manufacturing Company, East Pittsburgh, Pa., a corporation of Pennsylvania

Application November 13, 1935, Serial No. 49,512

5 Claims. (Cl. 250—36)

My invention relates to oscillation generators and more particularly to one of the dynatron type.

It is an object of my invention to provide such an oscillator, the frequency of which shall remain substantially unaffected by changes in effective load resistance.

Another object of my invention is to provide a generator of the above type wherein the changes necessary to render it unaffected by variations in effective load resistance are very slight.

An oscillation generator of the dynatron type relies upon the presence of a negative resistance characteristic for its operation. Primary electrons from the filament or cathode are caused to bombard the plate of the tube and liberate therefrom secondary electrons. By reason of the fact that a higher positive potential is impressed upon the grid of the tube than that impressed on the plate, secondary electrons emitted from the plate as a result of primary bombardment, are attracted to the grid electrode and produce current flow in the grid circuit. It is apparent from the above that whatever change the plate current may undergo by reason of oscillations generated in the plate circuit, the grid circuit will undergo corresponding changes since electrons leaving the plate are attracted by the grid and add to its current. A circuit capable of being tuned to the same frequency as the tank circuit, which is normally located in the plate circuit of the oscillator and placed in the grid circuit, will have oscillations induced in it.

In accordance with the teachings of my invention, I propose to insert such a tunable circuit in the grid circuit of a dynatron oscillator, and couple the load circuit to this tunable circuit, instead of the plate circuit, as is the customary practice, and then neutralize the oscillator to prevent load variations from altering the frequency characteristic of the circuit.

It is well known in the prior art that variations in load may cause such reactions upon the oscillation generator feeding the load as to produce a change in its frequency of oscillation. This holds good also for oscillators of the dynatron type where the load is coupled to the tank circuit, which is the circuit that determines the frequency of the generator.

By inserting a tunable circuit in the grid circuit of the oscillator, as proposed above, and then neutralizing the oscillation generator in a manner which will be hereinafter described, the load circuit is effectively isolated from the frequency determining or tank circuit, and as a result, var-

iations in load exert practically no influence upon the frequency of the oscillator.

In Fig. 1 and Fig. 2 of the accompanying drawing, I have illustrated two embodiments of my invention. In each of these embodiments I have disclosed an oscillator of the dynatron type comprising an electron discharge device 1 having a cathode 3, a grid 5 and a plate electrode 7 with the grid electrode having a higher positive potential impressed thereon than that impressed upon the anode.

In the circuit of Fig. 1, the tank circuit comprising an inductor 9 shunted by a tuning condenser 11 is connected in the plate circuit in series with a portion of the power supply source 13, the negative end of which is grounded. In the grid circuit I have interposed a resonant circuit comprising an inductor 15 and a shunting condenser 17 tunable to the frequency of the tank circuit. The grid 5 is connected to one terminal of this tunable circuit, whereas the extreme positive terminal of the power supply source 13 feeding the grid is connected to the midpoint or an intermediate point on the coil 15. For simplicity of illustration as well as economy in practical operation, the same source of supply is shown for delivering energy to both the grid and the anode, although separate sources may as well be employed. The filament is grounded to complete the grid and plate circuits of the oscillator.

Neutralization of the oscillator in this embodiment of my invention is obtained by connecting a small neutralizing condenser 19 between the free end of the grid tunable circuit and the plate 7 of the electron discharge device, thus completing a bridge circuit wherein each section of the grid coil 15 constitutes an arm of a bridge and the neutralizing condenser 19 and the grid plate capacity comprise the other two arms of the bridge circuit.

The load which is to be fed from the oscillator is coupled to the grid coil 15 and in view of the fact that the grid coil comprises two arms of a balancing bridge network, any variations in load will be neutralized in the bridge circuit and will not be communicated to the tank circuit. Since the tank circuit determines the frequency of the generator, it follows that the frequency thereof will not be affected as a result of any changes occurring in the effective load resistance.

In the second embodiment of my invention, as illustrated in the circuit of Fig. 2, the tank circuit comprising coil 21 and condenser 23 is made a part of the bridge network or neutralizing circuit instead of the tunable grid circuit 25—27.

50 55

Thus, the tuned circuit is connected in the grid circuit with the grid at one end and the other end connected to the power supply source.

The tank circuit on the other hand, is connected one end directly to the plate of the tube and a midpoint tap or an intermediate point to the power supply source for the anode. The free end of the tank circuit is then connected by means of a small neutralizing condenser 29 to the 5 grid 5 of the electron discharge device, thus completing the bridge network which now comprises the tank coil 21 as constituting two arms of the bridge and the neutralizing condenser 29 and grid plate capacity as constituting the other two arms. 10

15 Regardless of which modification or embodiment is relied upon, variations in load circuit cannot be transmitted to the tank circuit or frequency determining portion of the oscillator, and consequently, the frequency of the oscillator will 20 remain constant insofar as load changes may be involved.

While I have described my invention in great detail, various modifications may be made therein without departing from the scope of my invention, and I desire that only such limitations shall 25 be imposed thereon as are indicated in the appended claims.

I claim as my invention:

1. In combination, an electron discharge device 30 comprising cathode, anode and grid electrodes, a circuit connecting said grid and said cathode, said circuit including a source of positive potential for said grid a second circuit connecting said anode and cathode, said second circuit being connected to an intermediate point on and including a portion of said source of potential for said anode and an impedance element tunable to a desired frequency, said impedance element being connected to an intermediate point on said 35 source of potential, means for coupling said element directly to one of said positively biased electrodes and capacitively to said other positively biased electrode in opposing relation with respect to said intermediate point.
2. In combination, an electron discharge device 40 comprising a cathode, and anode and grid electrodes, an impedance, one point of which is conductively connected to said anode, another point thereon being capacitively connected to said grid, a source of potential supply connected 45 in circuit between said cathode and an intermediate point on said impedance, and a second impedance in series with a source of potential

supply of higher value than said first potential supply, connected in circuit between said cathode and said grid electrode.

3. In combination, an oscillation generator of the dynatron type comprising an electron discharge device having cathode, grid and anode electrodes, a circuit interconnecting said cathode with said grid and another circuit interconnecting said cathode and anode electrodes, said circuits being substantially free from regenerative coupling, means for maintaining said grid at a positive potential higher than said anode with respect to said cathode and means in said anode circuit for determining the frequency of said oscillation generator, said means comprising a 10 resonant tank circuit, and a load circuit coupled to derive energy from said grid circuit, and means 15 reactively interconnecting said circuits for neutralizing the effect of variations in said load circuit.

4. In combination an electron-discharge device comprising a cathode and a pair of other electrodes, the respective members of said pair being spaced from said cathode by different distances, a source of positive potential between said cathode and each of said pair, the potential between said cathode and the nearer of said pair being higher in a positive sense than the potential between the cathode and said electrode farther therefrom, an impedance having one portion thereof conductively connected to one of said pair and its associated source, and having another portion thereof capacitatively connected to the other of said pair, and a tuned circuit connected between said cathode and one of said pair.

5. In combination, an oscillation generator of the dynatron type comprising an electron discharge device having cathode, grid and anode electrodes a circuit interconnecting said cathode with said grid and another circuit interconnecting said cathode with said anode electrodes, said circuits being substantially free from regenerative coupling, means for maintaining said grid at a positive potential higher than said anode with respect to said cathode and means in said anode circuit for determining the frequency of said oscillation generator, said means comprising a resonant tank circuit, and a load circuit coupled to derive energy from said grid circuit, and a capacity interconnecting said grid and plate 50 circuits for neutralizing the effect of variations in said load circuit.

FREDERICK H. SCHEER.
